Specification for Design.

Patented Aug. 27, 1918.

Application filed April 26, 1918. Serial No. 231,040. Term of patent 14 years.

To all whom it may concern:

Be it known that I, LEOPOLD KRAUSS, a citizen of the United States, residing at Indianapolis, in the county of Marion and State of Indiana, have invented a new, original, and ornamental Design for Scottish-Rite Rings, of which the following is a specification, reference being had to the accompanying drawings, forming a part thereof.

In the drawings Figure 1 is an end view of the ring having my new design; Fig. 2 is a view of one side of the ring showing

one portion of the design; Fig. 3 is a view of the opposite side of the ring showing another portion of the design; and, Fig. 4 is a plan view of the complete design.

I claim:

The ornamental design for a Scottish Rite ring, as shown.

In testimony whereof I affix my signature in presence of two witnesses.

LEOPOLD KRAUSS.

Witnesses:

OSCAR L. CHAMNESS,
E. T. SILVIUS.
